UNITED STATES PATENT OFFICE.

JOHN E. CARR, OF AURORA, ILLINOIS, ASSIGNOR TO ALL-STELL-EQUIP COMPANY, OF AURORA, ILLINOIS, A CORPORATION OF ILLINOIS.

INCLOSED SWITCH.

Application filed July 1, 1920. Serial No. 393,303.

To all whom it may concern:

Be it known that I, JOHN E. CARR, a citizen of the United States, residing at Aurora, in the county of Kane and State of Illinois, have invented a certain new and useful Improvement in Inclosed Switches, of which the following is a specification.

My invention relates to inclosed or safety switches, more particularly of the externally operated type, and the objects of the invention are first, to provide means for preventing the opening of the box when the switch is in closed position; second, to provide means for preventing the closing of the switch when the box is open; and third, to provide a construction such that a padlock or other locking device may be employed for locking the switch open and thus preventing anyone from obtaining service unless it is approved by an inspector or other authorized person. In connection with these objects it is my purpose to accomplish the results in an economical, efficient and certain manner.

These objects are accomplished by the mechanism illustrated in the accompanying drawings in which—

Figure 1 is an assembly view in perspective showing the switch and box cover open; Figure 2 is a side elevation looking towards the left in Figure 1, the box being shown in section.

Figure 3 is a plan section on the line 3—3, Figure 2.

Figure 4 is a perspective view of the box with the cover closed, a portion of the cover being broken away to show the position of the operating link and locking arm.

Figure 5 is a side elevation looking towards the left in Figure 4.

Figure 6 is a plan section on the line 6—6, Figure 5.

Figure 7 is a fragmentary detail showing the means by which a padlock may be employed for keeping the box locked.

Like numerals denote like parts throughout the several views.

The box proper, indicated by the reference numeral 1, is preferably of sheet metal and is provided with a cover 2 which in the present case is hinged to it. Mounted within the box, preferably on the back wall, is a panel 4 of insulating material having stationary contacts 6, 6 adapted to be engaged by switch blades 7, 7 said blades being con-

nected by an insulating cross bar 8 so as to operate in unison. The blades are rotatable about stationary pivots 9. It is desirable to equip the panel with sockets 10 adapted to receive fuse plugs 11. The parts as thus far described, are well known, and the design may be varied without departing from the spirit of the invention. For convenience the blades 7 and cross bar 8 will be collectively referred to as "the switch" 65 altho they are in reality, simply the movable elements thereof.

Now referring to the parts more intimately connected with the essence of the invention: A rod 12 is pivotally connected 70 to the cross bar 8, preferably by means of a block 14. The bottom wall of the box has a slot or hole 17, preferably near the front edge, and the link, which is here shown as a flat bar, passes out thru it. A shoulder 75 or offset 15 is formed between the ends of the rod in such position that when the rod is drawn outward, and the switch is completely open, the shoulder will strike against the bottom wall of the box and limit the 80 movement. It is desirable to provide a ring 16 or other appropriate handle at the outer end of the rod to facilitate operating it. The portion of the rod below the shoulder 15 is long enough to permit the rod to be 85 raised sufficiently to enable the switch to be closed, as illustrated in Figures 4 and 5. It is desirable to provide a hole 18 in the rod 12 below shoulder 15. By passing the bow of a padlock thru this hole beneath the bottom of the box, the switch cannot be closed; thus enabling the superintendent in charge 90 to be assured that the switch cannot be closed except by one provided with a key for the purpose.

Now referring especially to the interlocking devices, a locking arm 20 is secured to the inside of the cover, as shown in perspective in Figure 1. It is here shown in the form of a plate and lies horizontal so as 100 to swing just above the bottom wall of the box. It has a segmental working edge 21 which is concentric with the axis of the hinges of the cover. In other words, the edge 21 is approximately a quadrant concentric with the axis of the cover. It is of such diameter as to enter well into a notch 22 formed in the adjacent side of the link 12 just above the shoulder 15. This notch 105 is shown in perspective in Figures 1 and 4. 110

So long as any part of the locking arm projects into the notch it prevents the rod from being pushed inward and thus prevents the switch from being closed. At the inner end 5 of the segmental edge of the locking arm 20 the metal is cut away to enable the arm to clear the rod so it can be raised for closing the switch. Differently stated, the locking arm is cut away near the inside of the 10 cover, so that when the cover is closed the locking arm will disengage itself from the rod and permit the rod to be pushed inward for closing of the switch. This cut in the locking arm forms a shoulder 26 and 15 the parts are so formed that unless the rod is pulled out so that the notch will lie in the plane of the locking arm, the shoulder 26 will strike the inside of the rod and prevent the cover from being swung open. 20 Thus the cover is locked shut except when the switch is open.

A lug 24 projects beyond the arc of the quadrant at the outer end (the end remote from the cover) as best shown in Figure 3. 25 It projects far enough to strike the inner side of the rod and thus forms a stop for limiting the outward swing of the cover. In fact, the locking arm 20 forms a stop operative upon the rod for preventing the rod 30 from being pushed in when the arm and cover are in open position, and the rod forms a stop operative upon the arm for preventing the arm and cover from being swung open when the rod is pushed in.

35 The operation will now be readily understood. So long as the cover remains closed the rod may be pushed inward or pulled outward for closing or opening the switch, but unless the rod is pulled outward to the limit 40 (and thus holds the switch open) the shoulder 26 will strike the rod and hold the cover closed. If, now, the rod is pulled fully outward the notch will come to the plane of the locking arm, thus permitting it to enter and 45 permitting the cover to be swung open. So long as the cover remains open the switch will be locked open. Thus, unless the switch has been opened the cover cannot be opened and so long as the cover remains open the 50 switch cannot be closed.

Frequently it is desired to prevent the closing of the switch regardless of whether the cover is closed or open. By inserting the bow of a padlock thru the hole 18 in rod 55 12 when the switch is open it will become impossible to close the switch. Usually the key to the padlock will be retained by an inspector or superintendent who will thus have control of the apparatus and be able to 60 prevent current from being supplied to the circuit which the switch box controls.

65 It will be noted that the results above described are obtained in a very simple and economical manner. Practically speaking, the interlocking of the switch and cover is

obtained simply by the aid of two elements, viz, the locking plate and the rod. These parts are of simple form and may be readily assembled. The locking arm is preferably in a plane near the plane of the bottom of 70 the box, and hence the rod need not be of particularly heavy construction because the leverage exerted upon it by the locking arm is consequently very slight; furthermore, the hole 17 thru which the rod emerges acts as 75 a guide and the metal surrounding it absorbs the strain in case any person should exert a strong pull on the cover in an attempt to open it. Thus a beneficial result is gained from the fact that the rod passes out thru 80 a hole in the wall of the box and the locking arm lies near the plane of the same wall.

Having thus described my invention what I claim as new and desire to secure by Letters Patent, is:

1. An externally operated inclosed switch 85 having a box, a cover hinged to it, a switch within the box, an operating rod connected to the switch and passing out through a hole in one of the walls of the box, said rod being movable approximately longitudinally for operating the switch and being arranged approximately parallel to the hinged axis of the box cover, the switch being open when the rod is pulled out, and a locking 90 arm fastened to the cover and adapted to engage and lock the rod when the latter has been pulled outward and the door has been 95 swung open.

2. An externally operated inclosed switch 100 having a box, a cover hinged to it, a switch within the box, an operating rod connected to the switch and passing out through a hole in one of the walls of the box, said rod being movable approximately longitudinally for 105 operating the switch and being arranged approximately parallel to the hinged axis of the box cover, the switch being open when the rod is pulled out, said rod having a shoulder facing inward, and a locking arm fastened to the inside of the cover and having a segmental working edge adapted to lie in front of the shoulder on the rod when the rod is pulled outward and the cover is 110 in various angular positions, partially or 115 fully open.

3. In combination, a switch box having a cover hinged to it, a switch within the box, an operating rod connected to the switch and passing out through a hole in the box, said 120 rod having an offset in it which forms one shoulder facing outward for limiting the distance to which the rod may be pulled outward, and a second shoulder facing inward, and a locking arm fastened to the cover and 125 adapted to project over the second shoulder for preventing the rod from being pushed in when the locking plate and cover are in open position.

4. In combination, a switch box having a 130

- hole in one of the walls, a hinged cover, a switch within the box, an operating rod connected to the switch and passing out through said hole, said rod having a shoulder facing inward, a locking arm fastened to the inside of the cover and having a segmental portion adapted to engage said shoulder when the cover is open and the rod is pulled outward, said locking arm also having a projection adapted to engage the back of the rod when the cover is open for limiting the distance to which the cover may be swung open.
5. In a device of the class described, the combination of a box, a hinged cover, an inclosed switch, a rod passing out thru a hole in the box and movable longitudinally for controlling the switch, the rod being cut away at one point, and the cover having a locking arm fastened to it, the arm lying in a plane at right angles to the rod and having a shoulder adapted to strike against the rod and hold the cover closed unless the cut-away portion of the rod lies in the 20 plane of the arm, said cutaway portion being in the plane of the arm when the switch is open.
6. In a device of the class described, the combination with the box, cover and inclosed switch, of a rod passing out thru a hole in the box and movable longitudinally to control the switch, the rod having a notch in the side, and the cover having a locking arm fastened to it, the arm lying in a plane at right angles to the rod and to the cover and having a shoulder adapted to strike against the rod and hold the cover closed unless the notch lies in the plane of the arm, the notch being in the plane of the 35 arm only when the switch is open.
7. An externally operated inclosed switch having a box, a cover hinged thereto, a switch within the box, a rod, arranged approximately parallel to the axis of the cover hinge, connected to the switch and movable longitudinally for operating it, the rod passing out thru a hole in one of the walls of the box and having a shoulder adapted to strike the wall of the box when the switch 45 is completely opened, the rod having a notch just inside of the shoulder; and a locking arm fastened to the inside of the cover in a plane parallel to and near the
- plane of the wall which has the hole in it, said locking arm having a working edge 55 concentric with the axis of the cover hinge adapted to enter and lie within the notch in all positions except the one corresponding to the closed position of the door.
8. An externally operated inclosed switch 60 having a box, a cover hinged thereto and adapted to swing about a vertical axis, a rod pivoted to the end of the switch for operating it, said rod being longitudinally movable vertically and passing out thru a 65 hole in the bottom of the box and having a shoulder adapted to strike the bottom of the box when the switch is completely open, a locking arm fastened to the inside of the cover in a plane slightly above the plane of 70 the bottom of the box, the arm and the rod being adapted to interlock and prevent the rise of the rod in all positions of the locking arm excepting that corresponding to closed position of the cover. 75
9. An externally operated inclosed switch having a box, a cover hinged thereto and adapted to swing about a vertical axis, a rod movable longitudinally and pivoted to the end of the switch for operating it, the 80 link passing out thru a hole in the bottom of the box and having a shoulder adapted to strike the bottom of the box when the switch is completely open, a locking arm fastened to the inside of the cover in a plane slightly above the plane of the bottom of the box, the arm and the rod being 85 adapted to interlock and prevent outward movement of the arm in all positions of the rod except that corresponding to the open 90 position of the switch.
10. An externally operated inclosed switch having a box, a cover hinged to the box, a switch within the box, a longitudinally movable rod connected to the switch 95 for operating it, the rod passing out thru a hole in one of the box walls perpendicular to the hinge axis, and an arm fastened to the inside of the cover and extending at right angles thereto, the arm having a lug 100 adapted to strike the inside of the rod for limiting the extent to which the cover may be swung open.

In witness whereof, I have hereunto subscribed my name.

JOHN E. CARR.
